(57) **CLAIM**

The ornamental design for a tissue roll holder, as shown and described.

DESCRIPTION

FIG. 1 is a top perspective view of a tissue roll holder showing our new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a rear elevational view thereof.

The broken line showing of the set screws in FIGS. 1, 6 and 7 are for purposes of illustration only and form no part of the claimed design.
